MACHINE FOR FLANGING
CYLINDRICAL SHELLS

Leon H. Johnson, Warren, Pa., assignor to Struthers Wells Corporation, Warren, Pa., a corporation of Maryland

Application June 10, 1946, Serial No. 675,611

12 Claims. (Cl. 153—29)

1

This invention relates to a machine for forming external annular flanges on the ends of cylindrical shells and similar articles and more particularly on shells which are made in relatively large sizes and of comparatively thick malleable metal, such as steel.

These flanges on the ends of cylindrical shells are utilized for bolting a plurality of such shells or attaching heads or other parts thereto by bolts or the like.

It is the object of this invention to provide a machine for this purpose whereby flanges may be formed on the ends of cylindrical shells expeditiously, accurately and economically and with a minimum expenditure of power and labor.

In the accompanying drawings:

Fig. 1 is a perspective view of a shell flanging machine embodying this invention and showing the position of the parts upon the completion of a flanging operation.

Figs. 2, 3 and 4 are fragmentary vertical transverse sections taken respectively on lines 2—2, 3—3 and 4—4; Fig. 5, the scale of Fig. 2 being the same as Fig. 5, but the scale of Figs. 3 and 4 being larger than that of Fig. 5.

Fig. 5 is a fragmentary vertical longitudinal section of the flanging machine showing the position of the parts at the beginning of the flanging operation on one end of a shell.

Fig. 6 is a similar view of the front part of the machine showing the position of the parts at the completion of a flange on a shell.

Fig. 7 is a fragmentary transverse section taken on line 7—7, Fig. 6.

Fig. 8 is a fragmentary horizontal section, on an enlarged scale, taken on line 8—8, Fig. 6.

Fig. 9 is a fragmentary cross section taken substantially horizontally on line 9—9, Fig. 5.

Fig. 10 is a similar view taken substantially vertically on line 10—10, Fig. 5.

Fig. 11 is a fragmentary sectional side view of the machine taken from the side opposite to Fig. 5.

Fig. 12 is a fragmentary cross section taken on line 12—12, Fig. 11.

Fig. 13 is a vertical cross section of the machine taken on line 13—13, Fig. 5, looking forwardly.

Fig. 14 is a fragmentary longitudinal section taken on line 14—14, Fig. 13.

Fig. 15 is a fragmentary transverse section taken on line 15—15, Fig. 14.

Fig. 16 is a diagrammatic front elevation of the hydraulic mechanism for moving into and out of its operative position the anvil upon which the flange of the shell is formed and the form-

2

ing roll is moved into and out of its operative position in forming a flange on the shell and then clearing the same.

Fig. 17 is a diagrammatic side elevation of this hydraulic mechanism.

In the following description the same numerals indicate like parts in the several figures of the drawings:

Although this machine can be used for forming flanges on the ends of sheet metal bodies which are variously curved in cross section the machine which is shown in the drawings is more particularly designed to operate on the opposite ends of a metal shell having a cylindrical body 15 and form peripheral flanges 21, 21, which project laterally therefrom in planes at right angles to the axis of the body, as shown in Figs. 1 and 6.

The main frame of the machine which supports the several working parts may be variously constructed but as shown in the drawings preferably comprises a base which includes transverse lower beams or bolsters 22 adapted to rest on the floor or foundation, lower longitudinal beams or stringers 23 secured upon said transverse beams and cross pieces 24 connecting said longitudinal beams; an elevated bench rising from the rear part of the base and including two longitudinal side plates 18 resting on the upper rear parts of the longitudinal beams 23 and provided with cross pieces 16 which are connected by bolts 19 with the upper parts of said beams, upper longitudinal side bars 17 arranged above the rear parts of the lower longitudinal beams and on opposite sides of the bench 18 and a plurality of upright posts 26 connected at their lower and upper ends with the respective lower longitudinal beams 23 and the upper longitudinal side bars 17.

While a flange is being formed on one end of the shell the same is supported on the base of the frame so that its axis is arranged horizontally and lengthwise of the machine and is capable of being rotated vertically about this axis. The means for thus supporting the shell are shown in Figs. 1 and 12—15 and constructed as follows:

The numeral 25 represents a pair of front supporting rollers which are adapted to engage with the underside of the body of the shell adjacent to the front end of the same and on opposite sides of the vertical center thereof. Each of these front supporting rollers is adjustably mounted on the adjacent part of the main frame so that it can be moved crosswise thereon and support the shell in the proper position.

relative to the mechanism which operates on the shell. The preferred construction of the means for this purpose are shown in Figs. 1, 13-15 and includes a horizontally and transversely adjustable slide 28 upon which the respective supporting roller 25 is journalled, a guideway 27 which is arranged on the upper end of one of the foremost posts 26 and upon which the respective slide 28 moves, an adjusting screw 29 working in a screw nut 30 on the slide and journalled on the frame so as to be capable of rotation but held against lengthwise movement, and a handle 31 secured to the outer end of this screw, for turning the latter and moving the respective supporting roller 25 relative to the shell body for properly supporting the same.

The numeral 32 represents two rear supporting rollers which are adapted to engage the underside of the body of the shell adjacent to the rear end of the same on opposite sides of the vertical center thereof. Each of these rear supporting rollers is mounted on a horizontally and transversely movable slide 33 which is guided on a guideway 34 formed on one end of a bolster 35 extending transversely underneath the shell. Each of the rear supporting rollers 32 and its slide may be adjusted transversely for bringing this roller in engagement with the body of the shell by an adjusting screw 36 engaging a screw nut 37 on the respective slide and turning in the bolster but held against lengthwise movement thereon and provided at its outer end with a handle 38 whereby the same is manipulated. This bolster supports both of the rear rollers 32 and their slides and is capable of adjustment on the main frame for properly supporting rollers to shells of different length. For this purpose the bolster 35 is slidable on longitudinal guideways 39 on the longitudinal beams 23 and is held in its adjusted position by fastening means which include a clamping block 40 engaging its opposite ends with the underside of the bolster and the adjacent part of the main frame, and a bolt 41 connecting said clamping block with this bolster, as best shown in Figs. 5 and 12.

Retaining means are provided which operate on the rear part of the shell for resisting rearward thrust on the same and also restraining rising of the part of the same while a flange is being formed on the front end of the shell, these retaining means being shown in Figs. 1-5 and constructed as follows:

Adjustable horizontally and lengthwise on the rear part of the main frame is a thrust slide 51 which includes a lower transverse plate 42 slideable at its opposite ends lengthwise of the machine on longitudinal guideways 43 on the side plates 18 of the bench, and adapted to be held in its adjusted position thereon by a clamping bar 44 engaging its opposite ends with the undersides of said guideways and clamped thereto by fastening bolts 45 connecting said clamping bar and slide plate, as shown in Figs. 4 and 5. When the bolts 45 are loose the thrust slide may be moved lengthwise to the desired position on the bench by an adjusting screw 46 arranged lengthwise in the upper part of the bench and mounted in bearings 47 thereon so that the same is held against longitudinal movement but is capable of being turned by a handle or hand wheel 47 on the rear end thereof, and a screw nut 48 mounted on the underside of the thrust slide plate 42 and engaged by the screw 46 so that upon turning the latter the thrust slide may be adjusted to the desired position lengthwise of the machine. On the

thrust slide is pivotally mounted by a vertical shaft 52, an end thrust roller 49 which has its axis arranged vertically and engages the front part of its periphery with the lower part of the rear end of the shell, as shown in Fig. 5, for the purpose of holding the shell against rearward movement while performing a flanging operation on the front end of the same. During this operation the rear end of the shell is also prevented from being lifted by a hold-down roller 50 which is pivotally mounted by a horizontal shaft 53, on the upper part of the thrust slide and in front of the end thrust roller 49, so that it turns about a horizontal longitudinal axis and bears with the lower part of its periphery against the upper inner side of the lower part of the shell, as shown in Figs. 3 and 5.

After the shell has been thus mounted at its underside on the supporting rollers and engaged at its rear part by the end thrust and hold-down rollers the front end of the shell is flanged by means which are constructed and operated as follows:

The numeral 54 represents an abutment or back-up roller which is adapted to bear against the upper or inner side of the front part of the shell at a distance from the front edge thereof during the operation of bending or forging the flange 21 on the front edge of the shell body 20. This back-up roller is preferably of cylindrical form and turns vertically about an axis which is horizontal and lengthwise of the machine. Only the lower part of the periphery of this back-up roller engages with the inner side of the shell and the same is mounted so that it is free to turn with the shell by frictional contact with the latter. The preferred means for thus mounting this roller includes a standard 55 arranged in front of the shell and mounted at its lower end on the front end of the main frame while its upper rear part carries the back-up roller. Although the latter may be rotatably mounted on this standard in various ways this is preferably accomplished by means of a hanger 56 depending from the upper rear part of this standard and provided at its lower end with a bearing 57 in which is journalled a horizontal longitudinal arbor 58 upon the front end of which the back-up roller is journalled, as shown in Figs. 1, 5 and 6.

In order to permit of adjusting the position of the back-up roller lengthwise of the shell to suit the desired width of the flange which is to be formed on the front end of the shell, means are provided for adjusting the standard 55 on the main frame which means preferably include a horizontal guideway 59 on the front part of the frame, a shoe 60 arranged on the lower end of the standard and slideable lengthwise on the guideway 59, an adjusting screw 61 mounted on the front part of the main frame so as to be capable of rotation but held against longitudinal movement, and a screw nut 62 mounted on the lower part of the standard 55 and engaged by this adjusting screw, as best shown in Fig. 5. After the standard has been shifted to the desired position by turning of the screw 61, the standard is held rigidly in place on the main frame by fastening bolts 63 passing through the shoe 60 and guideway 56, the latter being slotted, as shown at 64, to permit these bolts to move lengthwise of the frame the requisite extent.

Forming or forging the front end of the shell so as to produce an outwardly projecting flange 21 on the body 20 of the same is effected by means 75 which include a forging or forming roller 65

adapted to engage the upper or inner side of the lower front edge portion of the shell and bend the same from the horizontal position shown in Fig. 5 to the vertical position shown in Fig. 6. This forming roller is preferably of cylindrical shape and when in its fully retracted inoperative position shown in Fig. 5 the same is arranged in front of the back-up roller 54 and axially in line therewith and also of the same diameter so that the lowermost part of its periphery bears simultaneously against the inner side of the front end portion of the shell preparatory to bending the flange on the body of the shell. During the subsequent operation of the forming roller the same is bodily turned forwardly and downwardly 90 degrees from a position in which its axis is horizontal, as shown in Fig. 5 to a position in which its axis is vertical and thereby bends the shell so that the foremost edge portion thereof forms a right angled flange 21 on the body 20, in which last mentioned position the rearmost part of the forming roller bears against the vertical front side of the flange. After the forming roller has thus bent the flange on the body of the shell this roller is returned from the vertical position shown in Fig. 6 to the horizontal position shown in Fig. 5. The preferred construction of the means for thus actuating the forming roller is as follows:

The numeral 66 represents a carrier having a stud or arbor 67 on which the forming roller is pivoted and a quadrant shaped or segmental shoe 68 which slides with its outer curved side on an arcuate shaped or semi-circular guideway 69 on the rear side of the standard 55. The shoe 68 is confined against lateral displacement on the curved guideway 69 by segmental members or keepers 70 secured to opposite edges of this guideway by screws 71 and engaging with the corresponding edges of the shoe, as shown in Figs. 1, 5, 6, 8 and 13.

Actuating means are provided for moving the forming roller and its carrier forwardly and downwardly with a working stroke, and upwardly and rearwardly with an idle or return stroke, these actuating means being preferably constructed as follows:

The numeral 72 represents a vertically reciprocating cross head which is guided in guideways 73 on the standard 55 and which is moved downwardly with a working or power stroke by a hydraulic ram or motor the cylinder 74 of which has its upper end secured to this standard while its piston 75 has a piston rod 76 extending through the lower head of this cylinder and connected with the cross head, as best shown in Fig. 7. The numeral 77 represents two pulling chains or lines arranged along the opposite outer sides of the standard 55 and each passing with its lower intermediate part around a floating guide roller 78 on the adjacent side of the cross head 72 while its rear part is wound on the periphery of the segmental member or keeper 70 on the respective side of the forming roller shoe and connected therewith by a pin 79 and its fixed front end is secured by a pin 80 to the adjacent part of the standard.

Upon admitting a pressure medium into the upper end of the cylinder 74 the piston in the latter is forced downwardly together with the cross head 72 and floating guide rollers 78 whereby the intermediate parts of the pulling chains 77 are deflected downwardly in the form of a loop or bight and the rear stretches of these chains are unwound from the segmental mem-

bers, thereby moving the forming roller 65 from its elevated retracted position to its lowered advanced position and causing the same to forge a part of the flange 21 on the shell 20.

Return of the forming roller 65 from its foremost position in which it has completed its work to its rearmost position in which it begins its work is effected by two retracting chains or lines 81 arranged along the opposite outer sides of the standard 55 passing with its intermediate part around guide rollers 82 on the upper parts of this standard and having the rear parts wound around the segmental keepers 70 in a direction opposite to the rear parts of the pulling chains 77 and secured at their rear ends thereto by pins 83 while the front ends are secured to a vertically movable counterweight 84 arranged in front of the standard, as shown in Figs. 1, 5, 6, 7 and 8.

Upon permitting the pressure fluid to escape from the upper end of the power cylinder after the forming roller 65 has been moved into its lowermost or advance working position the piston 75 is permitted to rise under the pull of the weight 84 and return the forming roller to its elevated or retracted position.

Upon adjusting the standard lengthwise on the main frame by means of the adjusting screw 61 for bringing the back-up roller 54 into the desired position relative to the front part of the shell, the forming roller 65 is simultaneously moved therewith so as to bring the same to the desired position relative to the shell for bending the flange 21 on the body 20 thereof.

The numeral 85 represents a flanging roller or disk which constitutes part of the means for rotating the shell so that all parts of its front end are subjected to the operation of the flanging mechanism for producing an annular flange around the entire front end of the shell and which serves as a continuous support for the front end of the shell as successive parts of the same are brought into operative position relative to the back-up roller and the forming roller for progressively forming and completing the flange on the body of the shell. This flanging roller is arranged below the front part of the shell and adapted to rotate in a plane which is inclined at an angle of 45 degrees relative to the horizontal axis of the shell and the back-up roller and also the forming roller when the latter is in its fully retracted position. At its periphery the flanging roller is beveled so as to provide the same with an upper annular supporting face 86 the parts of which are successively arranged horizontally when they reach the uppermost and foremost position or operative area of this roller, and an annular anvil face 87 the parts of which are successively arranged vertically when they reach the uppermost and foremost position or operative area of this roller.

When the flanging roller is in its upper and foremost position the uppermost horizontal part of its supporting and driving face 86 engages the underside of the shell immediately below the back-up roller so that the shell is gripped between these rollers as shown in Fig. 5, and the shell is turned about its axis by the power applied to the flanging roller. While the shell is thus gripped and turned the forming roller 65 is turned bodily from the horizontal position shown in Fig. 5 to the vertical position shown in Fig. 6, whereby parts of the front end of the shell are successively turned from a position parallel with the axis of the shell to an outwardly projecting position at right angles to the axis

of the shell and against the vertical upper part of the anvil face 87 and thus forming the annular flange 21 on the front end of the body. In the operation of this machine the flange forming means are so controlled that the same effect the operation of forging the flange gradually and are maintained in their working position until the flange has been completed it being understood that the shell is rotated repeatedly about its axis until the desired results are attained.

The fulcrum about which the flange 21 is bent relative to the body 20 of the shell is located at the focal point between the apex or summit 88 of the two inclined faces 86 and 87 of the flanging roller 85 in the foremost and uppermost parts of these faces, and at the opposing lowermost peripheral parts of the back-up roller and the forming roller when the latter is in its fully retracted position. This focal point also constitutes the axis of the curved guideway 69 upon which the shoe 68 slides a quarter circle as it carries the forming roller 65 bodily around the uppermost part of the flanging roller.

Shifting means are provided whereby the flanging roller is moved toward and from the focal point 88 on an inclined plane of 45 degrees which extends through this point so that the highest part of the driving and supporting face 86 of this roller when in its forward elevated position will engage the underside of the body of the shell while the flange is formed thereon but when in its rearward lowered position will be disengaged therefrom and permit the flanged shell end to be removed and replaced by another unflanged shell end.

The shifting means for this purpose include a carriage which slides in inclined guideways 89 on the central part of the main frame and having a lower plate 90 which engages its opposite edges with said guideways, as shown in Figs. 9 and 10, and an upper plate 91 connected by webs 92 with the lower slide plate 90. The flanging roller 85 is arranged between the carriage plates 90 and 91 and pivotally mounted thereon by an inclined axle or shaft 93 journalled in bearings 94, 95 on these plates. This flanging roller carriage is reciprocated on the inclined guideways so as to move the foremost part of the flanging roller into and out of its operative position relative to the back-up roller and the forming roller. The forward movement of the flanging roller carriage is preferably accomplished by a hydraulic ram or motor which includes a hydraulic cylinder 96 mounted in an inclined position on the lower part of the main frame and containing a piston 97 which is connected by a piston rod 98 with the lower carriage plate 90, as shown in Fig. 5. Upon admitting fluid under pressure to the lower rear end of the hydraulic cylinder 96 the flanging roller carriage will be moved forwardly and upwardly and carry the flanging roller into its operative position and upon permitting the pressure fluid to escape from the lower end of this cylinder the flanging roller carriage will slide downwardly and rearwardly and carry the flanging roller into its inoperative position.

Driving means are provided for continuously rotating the flanging roller while the machine is in operation, these driving means being preferably constructed as follows:

The numeral 99 represents a driving shaft which is arranged horizontally and transversely above the rear part of the flanging roller carriage and journalled in bearings 100 thereon.

Motion is transmitted from this shaft to the flanging roller shaft 93 by an intermediate shaft 101 provided at one end with a driving gear wheel 102 which meshes with a driven gear wheel 103 on the lower end of the flanging roller shaft and provided at its opposite end with a worm wheel 104 which meshes with a worm 105 on the driving shaft, as shown in Figs. 5, 9 and 10.

The prime mover of this machine preferably consists of an electric motor 106 mounted in a fixed position on one side of the main frame so that its shaft 107 is above the driving shaft 99 of the flanging roller, as shown in Figs. 9 and 11. Motion is transmitted from the motor shaft 107 to the driving shaft 99 by a driving belt 108 passing around a small pulley 109 on the motor shaft 107 and a large pulley 110 on the driving shaft 99. The relative position of this driving shaft and this motor shaft is such that in the uppermost or foremost position of the flanging roller carriage the driving shaft 99 will be arranged above a line 111 extending from the axis of the motor shaft 107 at right angles to the path of movement of the flanging roller carriage, as shown by full lines in Fig. 11, and in the lowermost and rearmost position of the flanging roller carriage the driving shaft 99 will be arranged below said line 111, as shown by dotted lines in the same figure, the distances which the driving shaft move above and below the line 111 being equal, thereby maintaining a practically uniform tension of the driving belt 108 in all positions of the driving shaft 99 and insuring proper driving of the flanging roller without resorting to complicated driving mechanism.

In order to hold the flanging roller positively in its operative position as long as may be necessary to form the flange 21 on the body 20 of the shell, hand operated holding means are provided which are preferably constructed as follows:

The numeral 112 represents a vertically swinging locking arm which is pivoted at its rear end on the main frame by a transverse rock shaft 113 and provided at its front end with a cam or wedge 45 face 114 which is adapted to engage the rear end of the upper plate 91 of the flanging roller carriage, as shown in Figs. 5 and 9. When the flanging roller carriage is in foremost position the same is locked against backward movement by lowering 50 the holding arm and engaging its wedge 114 with the rear end of the flanging roller carriage, thereby positively holding the foremost part of the flanging roller in its operative position and insuring the formation of a uniform flange 21 on the shell body 20.

When the flanging operation has been completed the holding arm is raised out of engagement from the rear end of the flanging roller carriage thereby releasing the latter and permitting 60 the same to move downwardly and backwardly by gravity and carry the flanging roller away from the operating position and thus permit removal of the shell which has been flanged and replacing the same by another preparatory to flanging the 65 same. Raising and lowering of the holding arm out of and into its locking position may be effected by any suitable means, for example by a wrench or crank handle 115 applied to the outer end of the rock shaft 113, as shown by dotted lines 70 in Fig. 9.

Inasmuch as the wedge 114 on the holding lever engages the rear end of the flanging roller carriage so that it can only be released by considerable power, a releasing or jack screw 116 is mounted 75 ed on the front part of this arm in a position to

be engageable at its lower end with the rear part of the flanging roller shaft. After the operation of flanging a shell has been completed the jack screw 116 is turned in the direction for engaging its lower end with the flanging roller carriage and lifting the holding arm out of engagement therefrom, thereby releasing the flanging roller carriage and permitting retraction of the flanging roller into an inoperative position.

Various means may be employed for supplying a pressure medium to the cylinders 74, 96 of the hydraulic rams but those shown in Figs. 16 and 17, as an example, have been found satisfactory in practice and are constructed as follows:

The numeral 117 represents a supply tank adapted to hold a fluid pressure transmitting medium, such as oil. The liquid is withdrawn from this tank by a pump 118 which has its inlet connected by a pipe 119 with the tank and is driven by an electric motor 120 or other suitable prime mover. The outlet of this pump is connected with a relief valve 121 which has its outlet connected with a normal delivery pipe 122 adapted to deliver fluid at a predetermined pressure to the hydraulic ram cylinders 74, 96 but the delivery of fluid by this pump under excessive pressure to these cylinders is prevented by this relief valve which is so constructed that any excess pressure liquid is returned by a relief pipe 123 to the tank. The normal pressure delivery pipe 122 is provided with two branch pipes 124, 125, which lead, respectively, to the inlets of manually operated control valves 126, 127, the outlets of which are connected respectively, by pipes 128, 129 with the working ends of the ram cylinders 96, 74. The control valves 126, 127 are so constructed that when the parts thereof are in an open position liquid under pressure, is permitted to flow from the pump 118 into the cylinders 96 and 74 and thereby first move the flanging roller 85 into its operative position and then cause the forming roller 65 to subsequently move in an arcuate path around the uppermost part of the flanging roller, as previously described. After the flanging operation has been completed the control valve 127 is first reversed to cut off the pressure liquid from the forming cylinder 74 and permit the pressure liquid to escape therefrom through a branch return pipe 130 and allow the weight to pull the forming roller 65 to its retracted position. Thereafter the control valve 126 is also reversed to cut off the pressure liquid from the flanging cylinder 96 and permit the pressure liquid to escape therefrom through a branch return pipe 131 and thereby permit the flanging roller carriage to be re-turned to its rearward inoperative position. The branch return pipes 130, 131 are connected with a main return pipe 132 which leads back to the tank and returns the spent pressure liquid thereto so that the same can be circulated and used repeatedly during successive operations of the machine.

In order to control the speed of the bodily movement of the forming roller 65 during the operation of bending the flange 21 on the body 20 of the shell a regulating pipe 133 connects the branch pipe 129 leading to the cylinder 74 and is provided with a regulating valve 134 thereby permitting the required amount of pressure liquid to by-pass or bleed back to the tank as may be found necessary. Various accessories are employed in this liquid control system which are commonly used in apparatus of this general character, such as the gage 135 for indicating the liquid pressure in the piping of the forming cyl-

inder 14, detail explanations of which are unnecessary.

This machine is very strong and durable in construction and permits shells of comparatively heavy gauge metal to be flanged accurately and expeditiously, thereby effecting a substantial economy in doing work of this character.

I claim as my invention:

1. A machine for flanging metal shells and the like, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller, and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for effecting said arcuate movement of said forming roller including a standard provided with an arcuate guide-way, a carrier slidable on said guide-way and supporting said forming roller and means for moving said carrier including a segment on the carrier, a pulling line connected at one end with said standard and connected at its opposite end with said segment and adapted to be wound on the latter, a floating guide pulley engaging said pulling line, and a hydraulic ram having a movable cross head on which said floating guide pulley is mounted.

2. A machine for flanging metal shells and the like, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for effecting said arcuate movement of said forming roller including a standard provided with an arcuate guide-way, a carrier slidable on said guide-way and supporting said forming roller, and means for moving said carrier including a segment on the carrier, a pulling line connected at one end with said standard and connected at its opposite end with said segment and adapted to be wound on the latter, a floating guide pulley engaging said pulling line, a hydraulic ram having a movable cross head on which said floating guide pulley is mounted, a retracting line having its intermediate part guided on said standard and

11

one of its ends connected with said segment and adapted to be wound thereon in a direction opposite to said pulling line, and a weight connected with the opposite end of said retracting line.

3. A machine for flanging metal shells and like articles, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for bodily moving said flanging roller toward and from its operative position relative to the shell independently of said back-up roller and forming roller and in a path which is inclined relative to the axis of the article being flanged, including a frame on which said shell is adapted to be mounted and which is provided with an inclined guide-way arranged at an angle relative to the axis of the article being flanged, a carriage slideable on said guide-way and pivotally supporting said flanging roller, and means for reciprocating said carriage.

4. A machine for flanging metal shells and like articles, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for bodily moving said flanging roller toward and from its operative position relative to the shell independently of said back-up roller and forming roller and in a path which is inclined relative to the axis of the article being flanged, including a frame on which said shell is adapted to be mounted and which is provided with an inclined guide-way arranged at an angle relative to the axis of the article being flanged, a carriage slideable on said guide-way and pivotally supporting said flanging roller, and means for reciprocating said carriage including a hydraulic ram mounted on the frame and operatively connected with said carriage.

5. A machine for flanging metal shells and like articles, comprising a back-up roller adapted to engage the inner side of a shell adjacent to an

12

end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for bodily moving said flanging roller toward and from its operative position relative to the shell independently of said back-up roller and forming roller and in a path which is inclined relative to the axis of the article being flanged, including a frame on which said shell is adapted to be mounted and which is provided with an inclined guide-way arranged at an angle relative to the axis of the article being flanged, a carriage slideable on said guide-way and pivotally supporting said flanging roller, means for reciprocating said carriage, a motor fixed on the main frame, and means for transmitting motion from said fixed motor to the flanging roller on said movable carriage.

6. A machine for flanging metal shells and like articles, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for bodily moving said flanging roller toward and from its operative position relative to the shell independently of said back-up roller and forming roller and in a path which is inclined relative to the axis of the article being flanged, including a frame on which said shell is adapted to be mounted and which is provided with an inclined guide-way arranged at an angle relative to the axis of the article being flanged, a carriage slideable on said guide-way and pivotally supporting said flanging roller, means for reciprocating said carriage, a motor fixed on the main frame, and means for transmitting motion from said fixed motor to the flanging roller on said movable carriage including a driving shaft mounted on said movable carriage, pulleys mounted respectively on said driving shaft and a motor shaft forming a part of said motor, and belting passing around said driving pulley and said motor shaft pulley, said driving shaft being movable bodily with said carriage past the motor

shaft and equidistant on opposite sides of the same and thereby maintain substantially uniform tension on said belting in all positions of said carriage relative to said motor.

7. A machine for flanging metal shells and like articles, comprising a back-up roller adapted to engage the inner side of a shell adjacent to an end of the same, a flanging roller rotatable in a plane at an angle of 45° to the axis of said shell and having its periphery bevelled to provide an upper inclined face a horizontal part of which is adapted to bear against the underside of said shell opposite to said back-up roller and also provide a lower inclined face vertical parts of which are adapted to be arranged adjacent to the underside of the shell, a forming roller adapted to bear with its periphery against the end part of said shell on the same side as the back-up roller and movable bodily in an arcuate path from a position next to said back-up roller to a position in front of said flanging roller and operating to bend the end part of the shell from a position parallel with the body thereof to a position at right angles thereto and against the vertical part of the lower face of said flanging roller, and actuating means for bodily moving said flanging roller toward and from its operative position relative to the shell independently of said back-up roller and forming roller and in a path which is inclined relative to the axis of the article being flanged, including a frame on which said shell is adapted to be mounted and which is provided with an inclined guide-way arranged at an angle relative to the axis of the article being flanged, a carriage slidable on said guide-way and pivotally supporting said flanging roller, means for reciprocating said carriage, a motor fixed on the main frame, and means for transmitting motion from said fixed motor to the flanging roller on said movable carriage including an intermediate shaft mounted on said carriage and provided with a gear wheel which meshes with a gear wheel connected with said flanging roller, a driving shaft mounted on said carriage and provided with a worm which meshes with a worm wheel connected with said intermediate shaft, and a belt passing around pulleys mounted respectively on said driving shaft and the shaft of said motor.

8. A machine for flanging sheet metal shells and like articles, comprising a back-up roller adapted to engage the inner side of the shell to be flanged, an inclined flanging roller adapted to engage its periphery with the underside of said shell opposite the back-up roller, a forming roller adapted to engage the end of the shell and movable bodily for bending the end of the shell on the periphery of the flanging roller for producing a flange on the shell, a carriage movable toward and from said back-up roller and forming roller in a path arranged at an angle of 45° relative to the axis of said back-up roller, a frame upon which said shell is supported and which is provided with an inclined guide-way for said carriage, which guide-way is arranged at an angle relative to the axis of the article being flanged, actuating means for moving said carriage into and out of its operative position, and locking means independent of said actuating means for holding said carriage in a position in which it engages said shell during the flanging operation.

9. A machine for flanging sheet metal shells and like articles, comprising a back-up roller adapted to engage the inner side of the shell to be flanged, an inclined flanging roller adapted to engage its periphery with the underside of said

shell opposite the back-up roller, a forming roller adapted to engage the end of the shell and movable bodily for bending the end of the shell on the periphery of the flanging roller for producing a flange on the shell, a carriage movable toward and from said back-up roller and forming roller in a path arranged at an angle of 45° relative to the axis of said back-up roller, a frame upon which said shell is supported and which is provided with an inclined guide-way for said carriage, which guide-way is arranged at an angle relative to the axis of the article being flanged, actuating means for moving said carriage into and out of its operative position, and locking means independent of said actuating means for holding said carriage in a position in which it engages said shell during the flanging operation including a vertically swinging locking arm pivoted on said frame and provided with a wedge face which is adapted to engage with said carriage.

10. A machine for flanging sheet metal shells and like articles, comprising a back-up roller adapted to engage the inner side of the shell to be flanged, an inclined flanging roller adapted to engage its periphery with the underside of said shell opposite the back-up roller, a forming roller adapted to engage the end of the shell and movable bodily for bending the end of the shell on the periphery of the flanging roller for producing a flange on the shell, a carriage movable toward and from said back-up roller and forming roller in a path arranged at an angle of 45° relative to the axis of said back-up roller, a frame upon which said shell is supported and which is provided with an inclined guide-way for said carriage which guide-way is arranged at an angle relative to the axis of the article being flanged, actuating means for moving said carriage into and out of its operative position, and locking means independent of said actuating means for holding said carriage in a position in which it engages said shell during the flanging operation including a vertically swinging locking arm pivoted on said frame and provided with a wedge face which is adapted to engage with said carriage, and a manually operated rock shaft connected with said arm for moving the same into and out of engagement with said carriage.

11. A machine for flanging sheet metal shells and like articles, comprising a back-up roller adapted to engage the inner side of the shell to be flanged, an inclined flanging roller adapted to engage its periphery with the underside of said shell opposite the back-up roller, a forming roller adapted to engage the end of the shell and movable bodily for bending the end of the shell on the periphery of the flanging roller for producing a flange on the shell, a carriage movable toward and from said back-up roller and forming roller in a path arranged at an angle of 45° relative to the axis of said back-up roller, a frame upon which said shell is supported and which is provided with an inclined guide-way for said carriage, which guide-way is arranged at an angle relative to the axis of the article being flanged, actuating means for moving said carriage into and out of its operative position, and locking means independent of said actuating means for holding said carriage in a position in which it engages said shell during the flanging operation including a vertically swinging locking arm pivoted on said frame and provided with a wedge face which is adapted to engage with said carriage, and a jack screw member on said arm and adapted to be

engaged with said carriage for loosening the arm from said carriage.

12. A machine for flanging metal shells and the like, comprising a main frame upon which the shell is rotatably mounted and subjected to thrust toward one end thereof, a thrust roller adapted to engage the respective end of said shell and prevent lengthwise movement of the latter, a hold-down roller adapted to engage the inner side of said shell adjacent to said thrust roller, and a slide carrying said thrust roller and hold-down roller and adjustably connected with said frame.

LEON H. JOHNSON.
